UNITED STATES PATENT OFFICE.

FRANK. O. WORTHLEY, OF BOSTON, MASSACHUSETTS.

DESIGN FOR A PULLEY-BLOCK.

SPECIFICATION forming part of Design No. 20,693, dated April 28, 1891.

Application filed April 4, 1889. Serial No 306,032. Term of patent 3½ years.

To all whom it may concern:

Be it known that I, FRANK. O. WORTHLEY, a citizen of the United States, residing at Boston, in the county of Suffolk and State of Massachusetts, have invented and produced a new and original Design for a Pulley-Block, of which the following is a specification, reference being had to the accompanying drawing, forming part thereof.

10 The figure shows a front view of the cir-

cular block A, attached to star-shaped block-plate B.

What I claim is—

The design for a pulley-block, as shown and described, comprising the circular form of the pulley-block and the star-shaped block-plate.
